Attorney

UNITED STATES PATENT OFFICE.

JOHN M. MADIGAN, OF HAVERHILL, MASSACHUSETTS.

DIVIDED LAST.

Application filed November 14, 1924. Serial No. 749,884.

To all whom it may concern:

Be it known that I, JOHN M. MADIGAN, a citizen of the United States, residing at Haverhill, in the county of Essex, State of Massachusetts, have invented a new and useful Divided Last; and I do hereby declare the following to be a full, clear, and exact description of the invention, such as will enable others skilled in the art to which it applies to make and use the same.

The invention relates to divided lasts, and has for its object to provide a device of this character comprising a fore part and a heel part, and a link connection between said parts, which link connection is preferably tubular, and a locking device cooperating with the link for holding the parts in normal inoperative position. The locking device also forms means for holding the parts in operative position.

A further object is to pivotally mount the link in the bottom of a flared recess of the fore part, and to provide the fore part of the last with a transversely disposed U-shaped spring member between the arms of which the link is gripped and held for holding the parts in normal inoperative position or in operative position.

A further object is to provide the U-shaped spring member with a shank extending through an aperture in the bottom of the last and terminating in a headed member for holding the U-shaped member in position.

A further object is to provide cooperating members carried by the heel and fore parts of the last which prevent tacks and nails from entering between the parts of the last and interfering with the pivotal operation thereof.

With the above and other objects in view the invention resides in the combination and arrangement of parts as hereinafter set forth, shown in the drawing, described and claimed, it being understood that changes in the precise embodiment of the invention may be made within the scope of what is claimed, without departing from the spirit of the invention.

In the drawing:

Figure 1 is a vertical longitudinal sectional view through the last, showing the same in normal position.

Figure 2 is a view similar to Figure 1, but showing the parts in operative position.

Figure 3 is a detail sectional view taken on line 3—3 of Figure 1.

Referring to the drawing, the numeral 1 designates the fore part of the last, and 2 the heel part. The heel part 2 is provided with an aperture 3 for the reception of the reduced portion 4 and operating pin 5 or a bench dog if desired. Secured in a round recess 6 in the heel portion 2 by means of a transversely disposed pin 7 is a tubular link 8, which link fits tightly in the recess 6, consequently transverse play, as well as vertical play is obviated. Link 8 extends angularly out of the heel portion 2, and angularly into the flared recess 9 in the fore part of the last and is pivotally mounted in the bottom of the flared recess 9 on the transversely disposed pin 10. The recess 9 is of the same width as the tubular link 8, consequently the last sections 1 and 2 are maintained and rigidly held against transverse displacement in relation to each other, which is a common difficulty with devices of this character as at present constructed and which rapidly develop play incident to constant use. The tubular member 8 is made hollow to reduce the weight of the device to a minimum, however it is to be understood that the link may be made solid if desired.

It will be noted that when the forepart 1 is rocked on the pivot pin 10, its arcuate surface 11 will slidably engage the arcuate surface 12 of the heel portion 2, and the outer wide end of the tapered recess 9 will be closed at all times, thereby preventing tacks or other foreign matter from entering the recess 9 and interfering with the operation thereof, which has been found to be a common difficulty experienced with lasts at present constructed. The end 8^a of the tubular member 8 is round and arcuate in relation to the pivotal point 10, and closely engages the round bottom 13 of the recess 9; therefore it will be seen that there is a snug fit and the link will further brace the forepart 1 of the last, thereby reducing the strain on the pivot pin 10 and wear thereon. When the last section 1 is in inoperative position as shown in Figure 1, the wall 14 engages the side of the link 8 and maintains the sections 1 and 2 in proper registration. However to more substantially lock the parts in position a U-shaped spring 15 is provided within the recess 9, and which spring is carried by a pin 16 which extends through the last section 1

115

and is riveted at 17. It will be seen that when the tubular member 8 is forced between the spring arms 18, said spring arms will grip the opposite side of the tubular link 8, and will hold said last section 1 against movement on the pivot pin 10. Arms 18 are sufficiently long to extend beyond the center of the link 8, therefore it will be seen that a strong positive gripping action will take place. When the last is in operative position as shown in Figure 2, the last section 1 is limited in its movement by the engagement of the link 8 with the sides 19 of the recess 9, and will be held in said position as shown in Figure 2 by the spring action of the arms 18 cooperating with opposite sides of the link 8 to one side of the center of the link, therefore the U-shaped spring member holds the last section 1 in both of its extreme positions in relation to the heel last section 2. The U-shaped spring member 15 is preferably disposed in recesses 20 in the opposite walls of the flared recess 9, thereby allowing the link 8 to engage the opposite sides of the recess 9 for forming a more rigid structure, preventing wobbling and misalignment of parts. The inner end of the last section 1 is provided with a substantially angularly shaped portion 21, which is received in the similarly shaped recess 22 in the forward side of the last section 2, and which projection 21 braces the device as a whole, and at the same time additionally prevents the passage of nails or foreign matter into the working parts of the last. Last section 1 is also provided with a projection 23, which overlies the last section 2, and forms a portion of the instep contour of the last.

From the above it will be seen that a last is provided of the linked section type, which is simple in construction, rigidly braced, and provided with means cooperating with the link for holding the same in normal or operative position. It will also be seen that the link is thoroughly braced when in extreme position in either direction, and the recess in which the link is disposed is entirely closed at all times, thereby preventing nails or foreign matter from entering the recess, and interfering with the proper functioning of the movable parts of the last.

The invention having been set forth what is claimed as new and useful is:—

1. The combination with a shoe last, said last comprising a heel section, a fore section, of a cylindrical member carried by the heel section and extending into a tapered recess,

said cylindrical member being pivotally mounted in the recess inner end of the tapered recess and engaging the side walls of said recess, and a U-shaped spring member carried by one side of the tapered recess and cooperating with opposite sides of the cylindrical member for holding the same adjacent opposite sides of the recess.

2. The combination with a shoe last comprising a heel section and a fore part section, a link connecting said section and forming means whereby said sections may be removed in relation to each other, of an anchored gripping member disposed within one of the sections and cooperating with opposite sides of the link and forming means for holding the link in extreme positions in either direction.

3. The combination with hingedly connected shoe last sections, a cylindrical member rigidly connected to one of said sections and extending into a V-shaped recess in the other section, said cylindrical member being pivotally connected to one of the sections in the inner end of the V-shaped recess, the opposite sides of said recess cooperating with the cylindrical member for limiting the movement of the pivoted section, one of said sections entirely closing the V-shaped recess at all times, and a U-shaped spring member disposed in the recess and cooperating with the cylindrical member for holding the pivoted section in extreme positions.

4. The combination with a cylindrical link forming a connection between movable sections of a shoe last, one end of said link extending into a V-shaped recess and pivotally movable in said recess, of a U-shaped spring member anchored in one side of said recess and cooperating with opposite sides of the cylindrical link for gripping and holding the same in extreme inoperative and operative position.

5. The combination with a shoe last comprising sections movable in relation to each other, a tubular link connection between said sections, said link having one of its ends pivoted in the bottom of a V-shaped recess in one of the sections and movable therein, of a U-shaped spring member anchored in one side of said recess the arms of said U-shaped spring member cooperating with opposite sides of the link for holding the same in opposite extreme positions.

In testimony whereof I have signed my name to this specification.

JOHN M. MADIGAN.
